INVENTOR

William Hubbard

UNITED STATES PATENT OFFICE.

WILLIAM HUBBARD, OF ROCHESTER, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF FINISHING HEELS.

1,273,062.

Specification of Letters Patent. Patented July 16, 1918.

Application filed October 17, 1916. Serial No. 126,198.

To all whom it may concern:

Be it known that I, WILLIAM HUBBARD, a citizen of the United States, residing at Rochester, in the county of Monroe and State of New York, have invented certain Improvements in Methods of Finishing Heels, of which the following description, in connection with the accompanying drawings, is a specification, like reference characters on the drawings indicating like parts in the several figures.

This invention relates to a method of producing a heel having an ornamental stripe of contrasting color.

A stripe of this sort should possess a high degree of brilliancy in order to produce the desired ornamental effect; and for the same reason its boundary lines should be very straight and even and clearly marked so that the stripe shall stand out clearly in sharp contrast to the body of the heel. A stripe painted over the colored and polished heel does not have the desired brilliancy nor is the result much improved by first removing a strip of the coloring matter of the heel and then painting a stripe on the denuded area, since the material with which the heel is colored permeates the margins of the leather or leatherboard lifts so that in either case the desired brilliancy of the stripe and consequent sharp contrast between its color and that of the body of the heel is not secured. Moreover to produce by a painting operation a narrow, well defined stripe, the brilliancy of which is permanent is difficult.

According to the method of the present invention, a thin lift of aluminum or other colored material, impermeable by the ink or stain which is used to color the heel, is inserted between the permeable leather or leather board lifts which are used to make up the body of the heel. The heel with the impermeable lift incorporated in it is colored in the usual manner by having applied to its surface a coating more or less opaque according to whether a black or a russet heel is to be produced, after which the coloring material is cleaned from the edge of the impermeable lift leaving said edge as brilliant as before the coloring material was applied. By making use in this manner of a lift which is not permeable by the coloring material a brilliant, clearly defined stripe, which sharply contrasts with the remainder

of the surface of the heel, is readily produced.

Referring to the accompanying drawings,—

Figure 1 is an elevation of an unfinished heel having an impermeable ornamental lift;

Fig. 2 is an elevation of the heel after it has been colored and waxed;

Fig. 3 is an elevation of the finished heel showing the exposed edge of the ornamental lift;

Fig. 4 is a perspective of a portion of a heel burnishing machine fitted with mechanism for cleaning the edge of the ornamental lift, and

Fig. 5 is a perspective showing a heel in process of having the edge of the ornamental lift cleaned.

Referring now more particularly to Figs. 1, 2 and 3, there is shown a Louis heel made up of the usual leather or other lifts 7, an ornamental lift 9 which may be of celluloid, aluminum or other impermeable material, and the usual toplift 11. To this heel is applied either manually or by the use of a machine, a coloring matter such as blacking. The shoe is then taken to a heel burnishing machine where a coat of wax is applied and the coating smoothed and burnished. If the heel is to be finished in russet, the separate step of blacking or applying coloring matter to the heel is commonly omitted, such coloring matter being incorporated in the wax and applied by the burnishing machine. In either event, the heel, after being colored and burnished, presents the appearance shown in Fig. 2, the edge of the ornamental lift being obscured by the coating of finishing material.

The blacking and wax or other finishing material are then cleaned from the edge of the ornamental lift to give the effect shown in Fig. 3.

In Fig. 4 there is shown a portion of a heel burnishing machine which has been fitted with means for cleaning the edge of the ornamental lift. This machine is in general of a well-known form and will not be described in detail. It is provided with the usual iron 13 the function of which is to apply to the heel a coating of hot wax, with a smooth roll 15 to which the heel is next presented, and with a polishing brush

17 by which the wax is brushed in and polished.

Fast to the end of the rotary shaft 19 which carries the roll 15 and brush 17 is a wheel 21 the operative edge of which has substantially the same width as that of the ornamental lift, this edge comprising small teeth which rapidly remove the coloring matter and wax. In order to assist in the presentation of the heel to the cleaning wheel 21 a tread-rest 23 in the form of a plate is fastened at one end to a screw bolt 25, said bolt passing through ears on a bracket 27 and having at its inner end a square head which bears against a flat surface on the bracket and thereby prevents the bolt from turning. A thumb nut 28 provides means for moving the bolt, and with it the tread-rest, in and out. The bracket 27 is mounted on a pin 29 having at its outer end an eye, through which passes the stem of a bolt 30 which is threaded into said bracket, the bracket thus being angularly adjustable about the axis of the bolt 30. The pin is adjustably held in a socket in one end of a supporting member 31, the other end of which is adjustably fastened to one end of an arm 33 by a screw, the head or handle of which is indicated at 35. The hub at the end of the arm 33 is split and is adjustably fastened to a stationary rod 37 by a pinch-screw 39. The tread-rest may thus be adjusted in a path parallel to the axis of the bolt 25, angularly about the axis of the bolt 30, in a path parallel to the axis of the pin 29, and angularly about either the axis of the screw 35 or that of the rod 37. By these adjustments it is possible to provide for heels of different 40 shapes and for top lifts of different thickness.

The method of the invention is carried out as follows: The heel is first inked and blacked if the finished heel is to be given a black finish. It is then presented to the iron 18 and swung around until a coating of wax is applied to the whole lateral surface thereof. The waxed heel is then similarly presented to the smoothing roll 15 and thereafter to the brush 17. At this stage the lateral surface of the heel is covered with an opaque and burnished coat which obscures the edge of the ornamental lift. The heel is then presented to the cleaning wheel 55 21 in the manner shown in Fig. 5 and swung around so as to remove the coloring

matter and wax from the edge of the lift progressively beginning at a point in the junction of the lateral surface with the breast at one side of the heel and ending with a similar point at the other side of the heel. This ordinarily completes the treatment of the heel, but in some cases it is desirable to rub the cleaned edge of the lift and the adjacent coat of finishing material to remove the dust or chips and to polish the edge of the lift. When this further step is desirable, the heel is presented again to the roll 15 or brush 17 or to both.

The machine which has been described above is not claimed herein but forms the subject-matter of a divisional application Serial No. 222,131, filed March 13, 1918; and the heel having the lift of impermeable material forms the subject-matter of a pending application Serial No. 111,739, filed July 27, 1916.

Having thus described my invention, what I claim as new and desire to secure by Letters Patent of the United States is:

1. The method of producing a heel having an ornamental stripe which comprises assembling with a plurality of lifts of permeable material a lift of impermeable material, applying to the lateral surface of the heel so made up a coloring material which permeates the edges of the permeable lifts but merely coats the edge of the impermeable lift, and then removing the coloring matter from the edge of the impermeable lift while maintaining it undisturbed on the remainder of the heel.

2. The method of finishing a heel made up of leather lifts and an ornamental metal lift the edge of which is flush with the edges of the adjacent leather lifts which comprises coloring, waxing and burnishing the lateral surface of the heel and then removing the wax and coloring matter from the edge of the metal lift, beginning at a point in the junction of the lateral surface with the breast of the heel at one side of the heel and continuing progressively around said lateral surface to a similar point at the other side of the heel, and at the same time limiting the removing action to the area prescribed by the boundaries of the edge of the metal lift.

In testimony whereof I have signed my name to this specification.

WILLIAM HUBBARD.
